United States Patent Office

Des. 184,709
Patented Mar. 31, 1959

184,709

TOOTHBRUSH HOLDER

Fred M. Camp, Compton, Calif.

Application January 20, 1958, Serial No. 49,326

Term of patent 3½ years

(Cl. D4—3)

Fig. 1.

Fig. 2.

Fig. 3.

I claim:

The ornamental design for a toothbrush holder, as shown.
